UNITED STATES PATENT OFFICE.

GEORGE K. HAMILTON, OF LADLETON, NEW YORK.

HANDLE CONSTRUCTION.

Application filed October 31, 1924. Serial No. 746,933.

To all whom it may concern:

Be it known that I, GEORGE K. HAMILTON, a citizen of the United States, and residing at Ladleton, in the county of Ulster and State of New York, have invented certain new and useful Improvements in Handle Constructions, of which the following is a specification, such as will enable those skilled in the art to which it appertains to make and use the same.

This invention relates to handle constructions for use in connection with tools of various kinds and classes, such for example as shovels, spades, scoops, forks and the like; and the object of the invention is to provide a circular or ring-like hand member which will fit comfortably in the palm of the hand and which will facilitate the easy manipulation of the tool as compared with other handles or D's now in common use; a further object being to provide improved means for mounting the handle in connection with the shank of the tool and for reinforcing that part of the shank in connection with which the handle is mounted; and with these and other objects in view, the invention consists in a handle of the class and for the purpose specified, which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a perspective view of my improved handle construction and indicating one method of its use.

Fig. 2 is an enlarged face view showing the handle mounted in connection with the shank of a tool with parts of the construction broken away and in section.

Fig. 3 is a sectional view of the coupling and reinforcing member which I employ; and,

Fig. 4 is a side view of the member shown in Fig. 3.

Under the present practice of constructing tools of the class under consideration, the handle members or D's of the tools are provided with comparatively straight hand portions joining substantially parallel side portions extending from said hand portions,

and the corners formed by this construction render the handles or D's objectionable in use, in that the said corners and the straight hand portions put an undue strain or stress on the hand of the operator and cause the formation of callouses.

In carrying my invention into effect, I provide a substantially circular or ring-like D or handle member 5 preferably composed of suitable wood which is fashioned into the desired form by bringing flared end portions 6 into juxtaposition and forming a radial projection as seen in Fig. 2 of the drawing. The end portions 6 are preferably semi-circular in form whereby when they are joined together, the projection 7 formed thereby is substantially circular in form in cross section and is adapted to fit within a coupling member 8.

The coupling member 8 is fashioned from a tube of suitable material, one end portion of which is split to form separate parts 9 and 10 which are flared laterally and form a recess into which the handle member 5 is placed, and the parts 9 and 10 are semi-circular in form in cross section to correspond with and fit snugly on the handle member 5, and the free ends of said parts are preferably rounded as indicated at 11 to form a neat and finished appearance. The other end portion of the coupling member 8 is also split as shown at 12 and at right angles to the split in the first named end portion thereof to form independent parts 13 and the separate end portions of the member 8 are joined by an uninterrupted central tubular portion 14.

The parts 9 and 10 are provided with apertures 15 adjacent the free end portions thereof and with other oppositely disposed apertures 16 adjacent the central portion 14 or at the neck portion of the member 8, while the parts 13 are provided with two oppositely disposed apertures 17 and 18.

In mounting the handle member 5 in connection with the shank 19 of a suitable tool, for example a spade 20 as indicated in dot and dash lines in Fig. 1 of the drawing, the radially projecting member 7 formed by the flared end portions 6 is inserted into the coupling member 8, and a hole 21 is drilled through the member 7 or the portions 6 forming the same, said hole being in line with the apertures 16, and other holes 22 are drilled through the handle member and register with the apertures 15,

the last named holes being preferably drilled radially in the manner shown, and rods, bolts or the like 23 are passed through the holes 22 and apertures 15 to secure the 5 handle member 5 to the coupling 8 or the parts 9 and 10 thereof while a rivet or bolt 24 is passed through the hole 21 and the apertures 16 to reinforce the neck portion of the handle member and to securely retain 10 the end portions 6 within the coupling 8. In mounting the shank 19 in connection with the member 8, the shank is placed within the members 13 and fashioned to fit snugly therein, after which two holes 25 are drilled 15 through the shank 19 in line with the apertures 17 and 18 and rivets or bolts 26 are passed through the apertures 17 and 18 and the holes 25 to secure the shank 19 to the coupling member 8 and to reinforce the 20 mounting of the shank in connection therewith.

By splitting the shank end portion of the coupling member 8 to form the separate parts 13, I provide for the rigid and firm 25 mounting of the shank 19 in connection with the coupling member by a slight over-size in the shank which will cause a spreading or flaring of the parts 13 in the initial manufacture of the tool. In the event of the 30 shrinking of the shank within the coupling member, the same may be compensated for by simply tightening or resetting the rivets or bolts 26.

A handle member or D fashioned from 35 suitable material into substantially circular formation will, when used in connection with a suitable tool, provide for a more convenient manipulation of the tool and eliminate to a degree the stress and strain 40 on the hand of a workman using the tool, it being understood that the curvature and circular formation of the handle member 5 will be such as to provide a comfortable fit within the palm of the hand and also to permit 45 the grasping of the handle member throughout an arc of approximately 180 degrees in the different methods of handling and manipulating the tool. In other words, it is not always desirable to grasp the handle 50 member of a tool in line with the longitudinal plane of the shank, as it may be desired to grasp the tool within an arc of approximately 90 degrees from said longitudinal plane.

It will be understood that my invention 55 is not necessarily limited to the specific manner in which the handle member or D 5 is formed nor the use of any specific material in the formation thereof nor is my invention necessarily limited to the specific 60 construction of the coupling member 8 herein shown and described, and various other changes in and modifications of the construction herein set out may be made 65 within the scope of the appended claims same, the shank end portion of said coup-

without departing from the spirit of my invention or sacrificing its advantages.

Having fully described my invention, what I claim as new and desire to secure by Letters-Patent, is:—

1. A handle member for tools of the class described comprising a strip of predetermined material fashioned to form a substantially circular body, a coupling member for mounting said body in connection 75 with the shank of a tool, the end portions of said strip being brought together and projecting radially from said body and adapted to be inserted into and secured to said coupling member, and said coupling member 80 being provided with flared parts partially encircling said body.

2. A handle member for tools of the class described comprising a strip of predetermined material fashioned to form a substantially circular body, a coupling member for mounting said body in connection with the shank of a tool, the end portions of said strip being brought together and projecting 85 radially from said body and adapted to be 90 inserted into and secured to said coupling member, said coupling member being provided with flared parts partially encircling said body, and means passed through said coupling member and said body for retaining 95 said parts together and for reinforcing the same.

3. A handle member for tools of the class described comprising a strip of predetermined material fashioned to form a substantially circular body, a coupling member for mounting said body in connection with the shank of a tool, the end portions of said strip being brought together and projecting 100 radially from said body and adapted to be 105 inserted into and secured to said coupling member, said coupling member being provided with flared parts partially encircling said body, means passed through said coupling member and said body for retaining 110 said parts together and for reinforcing the same, the shank end portion of said coupling member being split to form separate parts between which the shank of a tool is 115 adapted to be placed.

4. A handle member for tools of the class described comprising a strip of predetermined material fashioned to form a substantially circular body, a coupling member for mounting said body in connection with the shank of a tool, the end portions of said strip being brought together and projecting 120 radially from said body and adapted to be 125 inserted into and secured to said coupling member, said coupling member being provided with flared parts partially encircling said body, means passed through said coupling member and said body for retaining 130 said parts together and for reinforcing the same, the shank end portion of said coup-

ling member being split to form separate parts between which the shank of a tool is adapted to be placed, and means for securing the shank within the last named end portion of said coupling member.

5. A handle member for tools of the class described comprising a strip of wood fashioned to form a substantially circular body, a tubular coupling member adapted to be mounted on the shank of the tool, the end portions of said strip being brought together and projecting radially from said body and adapted to be inserted into said coupling member and secured therein.

10 6. A handle member for tools of the class described comprising a strip of wood fashioned to form a substantially circular body, a tubular coupling member adapted to be mounted on the shank of the tool, the end portions of said strip being brought together and projecting radially from said body and adapted to be inserted into said coupling member and secured therein, and that portion of said coupling member

25 mounted on the shank of the tool being split.

7. A handle member for tools of the class described comprising a strip of wood fashioned to form a substantially circular body, a tubular coupling member adapted 30 to be mounted on the shank of the tool, the end portions of said strip being brought together and projecting radially from said body and adapted to be inserted into said coupling member and secured therein and 35 that portion of said coupling member mounted on the shank of the tool being split and the other end portion of said coupling member being flared and partially encircling said body.

8. A handle member for tools of the class described comprising a circular body having a radially projecting portion composed of separate abutting parts, and a coupling member secured to said projecting portion 45 by means of which said handle member may be secured to the shank of a tool.

In testimony that I claim the foregoing as my invention I have signed my name this 22nd day of October 1924.

GEORGE K. HAMILTON.
